UNITED STATES PATENT OFFICE.

GUSTAV A. FORSBERG AND THOR W. GRANBERG, OF CHICAGO, ILLINOIS.

TRACKING DEVICE FOR PLAYER PIANOS.

Application filed May 31, 1924. Serial No. 716,913.

To all whom it may concern:

Be it known that we, GUSTAV A. FORSBERG and THOR W. GRANBERG, citizens of the United States, residing at Chicago, in the county of Cook and State of Illinois, having 5 jointly invented certain new and useful Improvements in Tracking Devices for Player Pianos, do hereby declare that the following is a full, clear, and exact description of the same.

In the accompanying drawings, which illustrate a practical embodiment of the several features of our invention, Fig. 1 is a view in front elevation showing the mechanism in playing position and with parts in section at the music-roll chucks; Fig. 2 is a view in front elevation showing the mechanism in re-roll position; Fig. 3 is a view in rear elevation with the parts in the general 15 positions shown in Fig. 2; Fig. 4 is a detail view on an enlarged scale partly in bottom plan and partly in section taken on the line 4—4 in Fig. 3; Fig. 5 is a detail view in rear elevation on an enlarged scale 20 showing certain of the parts in their positions shown in Fig. 1, and Fig. 6 is a fragmentary view on an enlarged scale partly in section and partly in elevation.

In the drawings the reference numeral 1 30 designates the usual spool-box mounted on the shelf 2 in the piano case and in which the take-up spool 3 and the longitudinally slidable chucks for the removable music or note sheet roll 4 are journaled. The left 35 roll-chuck comprises a shaft 5 journaled in an extended bearing 6 on a plate 7 attached to the wall of the box, and is normally pressed inwardly by a spring 8 to revolubly support one of the flanges of the roll 4 and 40 has a collar 9 to limit its inward movement. The right roll-chuck comprises a shaft 10 suitably journaled in the transmission frame 11 attached to the wall of the spool-box and having adjustable inner and outer collars 45 12 and 13 respectively; the inner end of the collar 12 has means to engage the drive flange of the roll 4 when the latter is inserted between the chucks as shown in Fig. 1 and the outer end of the shaft 10 carries a fixed sprocket 14 by which the roll 4 may be driven to rewind the sheet of music 50 15 thereon. The take-up spool 3 is adjustable axially by usual suitable means and is revolved by a fixed gear 16 to move the music-sheet 15 over the tracker-bar 17; the usual transmission to which motion is im-

parted from the motor to roll the music-sheet 15 on the spool 3 and re-roll it on its roll 4 is not shown.

The means for securing the proper tracking or alignment of the music-sheet as it passes over the tracker-bar comprises a lever carrying an edge-guide adjacent an edge of the sheet and pneumatic means controlled by the lever for adjusting the sheet-roll axially of the tracker bar. The control lever 18 is pivoted at 19 near its rear end on a bracket 20 fixed on the left-hand wall of the spool-box in rear of the tracker-bar, and carries at its forward free end a finger or edge-guide 21 which overlies the tracker-bar and is adapted to contact with the left-hand edge of the music-sheet. The lever 18 carries near its rear end or pivot a disc-valve 22 which controls the inlet port of a pipe 23 which is mounted at its open end on an angular arm of the bracket 20 and by which atmospheric air is admitted to a port 24 of a tracker bellows or pneumatic 25 which is mounted on a bracket 26 on the box and has a duct 27 connected by a pipe 28 to the suction mechanism, such as the exhaust-bellows (not shown). The duct 27 is restricted by a bleedhole 29 to equalize the exhaust of air from the pneumatic 25 with the amount of atmospheric air that normally leaks past the valve 22 into the pipe 23; a clean-out opening giving access to the bleed-hole is provided and may be closed by a set-screw 30. A light spring 31 mounted between the spool-box and the lever 18 stresses the lever in its playing or normal position as shown in Figs. 1 and 5, which partially closes the valve 22 and abuts the finger 21 on the edge of the sheet 15. The tracker pneumatic 25 is mounted vertically with its apex or pivoted end uppermost and is expanded by a spring 32; its movable leaf 33 carries a fixed vertical arm 34 which projects above and below the leaf, and one end of a horizontal rod 35 is adjustably connected to the upper end of this arm by opposite nuts 36 threaded thereon; the other end of the rod 35 is pivoted to the upper end of a lever 37 fulcrumed at its lower end at 38 on a bracket 39 carried by the transmission-frame 11 on the spool-box. The lever 37 abuts against the right-hand end of the sliding shaft 10 of the music-roll, and it is apparent that these parts are in pneumatic balance and as the pneumatic 25 is collapsed more or less the sheet-roll 4 will be moved.

to the left and the spring 8 put under tension, and that as the pneumatic is allowed to expand the sheet-roll will be moved to the right under the stress of the spring 8. 5 In assembling the parts the playing or normal position of the finger 21 is taken as a guide or gauge, and such initial adjustments of parts are made as will ensure proper alignment of the sheet with the 10 tracker-bar when its edge is against the finger. If in the playing of the instrument the sheet moves to the left out of proper alignment with the tracker-bar the valve 22 will be moved by the finger 21 to open 15 or enlarge the port of pipe 23 to the atmospheric air, and as this intake of air is now larger than the amount sucked through the bleedhole 29 the pneumatic 25 will expand under the action of its spring and move the 20 music-roll to the right to its proper tracking position. If the sheet moves to the right out of proper alignment, the finger 21 is free to follow it and the valve 22 under the pressure of its spring 31 will move to 25 close or restrict the port of the pipe 23 to correspondingly cut-off the supply of air to the pneumatic 25 which causes the latter to collapse and move the music roll to the left. In either case the sheet is restored to 30 proper alignment with the tracker-bar.

The operation of tracking-devices such as herein described is greatly facilitated if the note sheet is correctly rewound upon its roll, as then the subsequent tracking of the sheet 35 when it is again inserted in the instrument will be more accurate. As the tracking-device functions during the playing of a composition and secures correct lateral adjustment of the sheet on the tracker-bar, the 40 music-roll is usually in proper alignment with the take-up spool when its sheet is finished. But in rewinding the sheet the exhaust is cut off from the pneumatic 25, and as the tracking-device is then unbalanced and inactive the music-roll is forced 45 to the right by its spring, and if the sheet is then rewound it will be unevenly rewound thereon. One of the features of our 50 invention is the provision of pneumatically controlled means whereby the music-roll 4 is locked in correct alignment with the tracker-bar and take-up spool when the playing of a note sheet is finished and is held in that final position during the rewinding 55 of the sheet, so that the sheet will be evenly rewound on its roll. Also, in rewinding the note sheet on its roll it is desirable to withdraw the control-finger 21 of the tracking-device from contact with its edge, and one 60 of the features of our invention is the provision of pneumatically controlled means to accomplish this purpose.

In the preferred embodiment of our invention a single pneumatic controlled by the 65 main exhaust operates means during the re-

winding operation to hold the tracking-device in position to align the music-roll with the take-up spool, and also means to move the control-finger away from the edge of the sheet. As here shown the fixed leaf of the 70 pneumatic 25 carries the fixed leaf 40 of an auxiliary bellows or pneumatic 41 having an expanding spring 42; a duct 43 (Fig. 6) leading through the fixed leaves of both pneumatics into the duct 27 establishes communication with exhaust pipe 28. The pneumatic 41 is mounted with its apex or pivoted end lowermost, and its movable leaf 44 carries at its free end a fixed wing 45 in which one end of a rod 46 is adjustably held by opposite nuts 47 threaded thereon; the free end of the rod passes freely through a guide 48 integral with the bracket 20 and abuts against the outer end of a rearwardly projecting tail 49 of the lever 18 when the 80 pneumatic 41 is expanded and moves the finger 21 away from the edge of the sheet 15, and when the pneumatic 41 is collapsed the rod is withdrawn from the tail to permit the spring 31 to move the finger into its normal position in contact with the sheet. By pivoting the control-lever 18 at the rear of the spool-box and mounting the valve 22 on the lever near its pivot the leverage provided by the distance from the pivot to the control-finger 21 affords sufficient power to allow the latter to move the valve easily and readily under slight stress of the sheet, so that any danger of valve-sticking is obviated. Also, the leverage provided by the 90 tail 49 of the valve is so great that a slight movement of the rod 46 will be sufficient to quickly open the valve and withdraw the finger 21 from contact with the sheet. The movable leaf 44 carries at its pivoted end an outwardly projecting arm 50 to one side of which the inner end of a ratchet-bar 51 is flexibly pivoted at 52, the free end of the bar projecting outwardly into the plane of an inwardly facing pawl 53 formed on the 100 lower end of the arm 54 on the movable leaf 33 of the pneumatic 25. The outer end of the arm 50 is formed with a beveled lip 54 which overlies a lateral pin 55 on the ratchet-bar, and a spring 56 mounted on the fixed leaf 40 holds the pin against the lip when the pneumatic 41 is collapsed, the bar being then rocked down out of the path of the pawl by the lip 54 engaging the pin 55 as shown in Fig. 5. The inner face of the pawl and the outer end of the bar are oppositely beveled 110 so that the pawl may readily pass back onto the bar in case the expansion of the pneumatic 25 carries the pawl beyond the outer end of the bar; the pin 55 engaging the lip 54 prevents the bar from rising beyond the range of these beveled portions.

When a note sheet is positioned and the exhaust apparatus is operated for playing purposes, the auxiliary pneumatic 41 is held 115

collapsed by the suction through the pipe 28, and the finger-operating rod 46 and the ratchet-bar 51 occupy their inoperative positions as shown in Fig. 5; at the playing only 5 the tracking-device operates as above described. When the playing of a sheet is finished the tracking-device remains temporarily in balance with the sheet in alignment with the tracker-bar and the music-roll approximately in alignment with the take-up spool. When the sheet-rerolling mechanism is operated the suction or exhaust is cut-off from the pipe 28 in the usual way, and the pneumatic 41 expands under the action of 10 its spring 42. During the initial expansion of the pneumatic 41 the rack 51 engages the pawl 53 to hold the pneumatic 25 against further expansion and preserve the tracking-device in balance in the final position it occupies 15 when the playing of the sheet was finished, whereby the sheet is aligned with the tracker-bar and the music-roll is held in substantial alignment with the take-up spool for proper rewinding of the sheet. The 20 rack 51 when operated can engage the pawl 53 in any position of the tracker-pneumatic 25 in its entire working range, and when the playing of a roll is finished the tracker-pneumatic and the tracking-device are automatically locked in the final positions they 25 then occupy. The flexible joint of the rack-bar allows the pawl to remain in engagement with the bar and preserve the pneumatic 25 in fixed position and the tracking-device in 30 balance while the pneumatic 41 further expands as shown in Figs. 2 and 3, and when the pneumatic 41 is sufficiently expanded the rod 46 engages the tail of the control-lever 18 and moves the finger 21 away from 35 the edge of the sheet. The interlocking of the auxiliary pneumatic 41 and the tracking-device pneumatic 25 holds the latter in fixed position during the rewinding of the sheet on its roll and prevents it from expanding and destroying the lineup of the music-roll and take-up spool. This interlocking occurs automatically and in timed 40 relation, and the withdrawal of the finger 21 from the edge of the sheet is properly 45 timed by the adjustment of the rod 46. After 50 the sheet is rewound on its roll and removed from the chucks the parts return to their normal positions shown in Figs. 1 and 55 to receive another music roll.

We claim:

1. A tracking mechanism for player pianos including a tracker bellows having a port and operative during piano playing, means operatively connected to the movable leaf of said bellows for effecting adjustment of a music-roll in relation to a tracker-bar, a tracking-controller co-operating with said port and with an edge of a music-sheet on the roll, an auxiliary bellows operative during 60 the rewinding of the sheet on its roll, 65

and means controlled by the auxiliary bellows and operative at the completion of the playing of a sheet to lock the tracker bellows in the position it then occupies.

2. A tracking mechanism for player pianos including a tracker bellows having a port and operative during piano playing, means operatively connected to the movable leaf of said bellows for effecting adjustment of a music-roll in relation to a tracker-bar, a tracking-controller co-operating with said port and with an edge of a music-sheet on the roll, an auxiliary bellows operative during the rewinding of the sheet on the roll, and a ratchet mechanism controlled by said auxiliary bellows to hold said tracker bellows from expanding during such rewinding beyond the position it occupies when the playing of a sheet is finished.

3. A tracking mechanism for player pianos including a bellows having a port and operative during piano playing, means operatively connected to the movable leaf of said bellows for effecting adjustment of a music-roll in relation to a tracker-bar, a tracking-controller co-operating with said port and with an edge of a music-sheet on the roll, an auxiliary bellows operative during the rewinding of the sheet on the roll, a pawl on the movable leaf of said first bellows, and a rack on the movable leaf of said auxiliary bellows constructed to engage said pawl and hold said first bellows from expanding during such rewinding.

4. A tracking mechanism for player pianos including a bellows having a port and operative during piano playing, means operatively connected to the movable leaf of said bellows for effecting adjustment of a music-roll in relation to a tracker-bar and including an arm having a pawl at one end, a tracking controller co-operating with said port and with an edge of a music-sheet on the roll, an auxiliary bellows operative during the rewinding of the sheet on the roll, and a rack operated by said auxiliary bellows to engage said pawl and hold said first bellows from expanding during such rewinding.

5. A tracking mechanism for player pianos including a bellows having a port and operative during piano playing, means operatively connected to the movable leaf of said bellows for effecting adjustment of a music-roll in relation to a tracker-bar, a tracking-control finger pivoted in the rear of the spool-box and co-operating with said port and with an edge of a music-sheet on the roll, an auxiliary bellows operative during the rewinding of the sheet on the roll, a rearwardly extending tail on said finger and a rod operated by said auxiliary bellows to contact with said tail to withdraw said finger from the edge of the sheet during such rewinding.

6. A tracking mechanism for player pianos including a tracking bellows, means operatively connected to the movable leaf of said bellows for effecting adjustment of a music-roll in relation to a tracker-bar, a pawl on the movable leaf of said bellows, an auxiliary bellows operative during the rewinding of the sheet, and a spring-pressed rack pivoted on said auxiliary bellows to engage said pawl and hold said tracking bellows in balance during such rewinding.
7. A tracking mechanism for player pianos including a bellows having a port and operative during piano playing, means operatively connected to the movable leaf of said bellows for effecting adjustment of a music-roll in relation to a tracker-bar and including an arm having a pawl at one end, a tracking-controller co-operating with said port and with an edge of a music-sheet on the roll, an auxiliary bellows operative during the rewinding of the sheet on the roll, a rack flexibly mounted on the movable leaf of said auxiliary bellows to engage said pawl and hold said first bellows in balance during such rewinding, and means operated by said auxiliary bellows to withdraw said controller from the edge of the sheet.
8. A tracking mechanism for player pianos including a bellows having a port and operative during piano playing, means operatively connected to the movable leaf of said bellows for effecting adjustment of the music-roll in relation to a tracker-bar and including an arm having a pawl at one end, a tracking-control finger co-operating with said port and with an edge of a music-

sheet on the roll, an auxiliary bellows operative during the rewinding of the sheet on the roll, a rack flexibly mounted on the movable leaf of said auxiliary bellows to engage said pawl and hold said first bellows in balance during such rewinding, and a rod operated by the movable leaf of said auxiliary bellows to withdraw said finger from the edge of the sheet.

9. In a player piano, the combination of a tracker-bar, a music-sheet roll, means including a take-up spool to pass said sheet over said tracker-bar, means acting upon said sheet roll and operative during the playing of the instrument to secure correct lateral adjustment of the sheet on the tracker-bar, and pneumatic means operative at the completion of the playing of the sheet to preserve the alignment of its roll with the take-up spool in the position the roll then occupies.

10. In a player piano the combination of an endwise adjustable music-sheet roll, a tracker-bar, means including a take-up spool for passing said sheet over the tracker-bar, means operative during the playing of the instrument to laterally adjust said roll in proper alignment with said spool, a bellows operative during the rewinding of said sheet on its roll, and ratchet mechanism controlled by said bellows to preserve the roll in alignment with the spool.

In testimony whereof we affix our signatures.

GUSTAV A. FORSBERG.
THOR W. GRANBERG.
